UNITED STATES PATENT OFFICE

CLIFFORD F. MORAIN, OF WEST TULSA, OKLAHOMA

PIPE COATING MACHINE

Application filed July 13, 1928. Serial No. 292,489.

My invention relates to painting machines and more particularly to a machine of that character for applying coatings of paint or enamel to pipe lines; the principal object 5 of the present invention being to effect an even and thorough distribution of the paint or enamel over the surface of the pipe and to expedite the progress in applying such coatings.

10 In accomplishing these and other objects of the invention, I have provided improved details of structure the preferred forms of which are illustrated in the accompanying drawings, wherein:

15 Fig. 1 is a perspective view of the machine illustrating its use in painting a pipe line.

Fig. 2 is a vertical section through the elevating mechanism and its supporting frame.

20 Fig. 3 is a vertical section through the distributing mechanism and its supporting frame.

Referring in detail to the drawings:

25 1 designates a pipe line such as ordinarily employed for conveying crude petroleum or the like between distant points of production and use. The pipe lines are usually laid in trenches such as 2 and are coated with paint or enamel previously to being laid in order to prevent excessive rust or corrosion 30 due to the underground moisture.

The pipe line is supported above the trench by means of suitable supports 3, and my apparatus 4 for applying the paint or enamel is movably positioned on the pipe between the 35 supports which are shifted along the pipe line as the coating operation proceeds.

The coating apparatus 4 includes a paint containing receptacle 5 substantially rectangular in shape, having an open upper end 6 and comprising side walls 7, bottom plate 8 and end walls 9, the forward end of the receptacle being provided with a sloping bottom portion 10 for cleaning purposes.

40 45 Slots 11 are centrally located in the upper edges of the end walls 9 to receive the pipe and to permit the upper edges of the receptacle side walls 7 to extend above the bottom side of the pipe and thereby serve as splash guards while the coating is being applied to the pipe.

Attached to the rearward end and the upper edges of the receptacle side walls 7 is a carrier frame 12 comprising beams 13 having upwardly offset portions 14 and horizontal portions 15 extending rearwardly from the offsets, a platform 16 being mounted on the beam portions 15 for carrying a motor 17 and power transmission mechanism 18 for purposes hereafter described. 55

Secured to the rearward ends of the beam portions 15 are brackets 19 carrying a concave roller 20 engaging the pipe 1 for movably supporting the rearward end of the apparatus from the pipe.

Mounted in suitable bearings 21 at the forward end of the beam portions 15 is a shaft 22 having a concave drive roller 23 keyed thereon and engaging the pipe, and a worm gear 24 formed integrally with the roller is engaged by a worm 25. 70

The worm 25 is fixed to the forward end of a shaft 26 extending rearwardly into the transmission 18, the transmission being of an ordinary variable speed type, and having connection with the motor 17 through a connecting shaft 27. 75

The shaft 26 is adapted for change to various speeds relative to the shaft 27 by a control lever 28 which may be shifted to change the gear ratios between the respective shafts. Rotation of the shaft 26 is imparted to the pipe-supported drive roller 23 through engagement of the worm 25 with the gear 24 and thereby the apparatus is moved along on the pipe line. 80

Fixed to the shaft 26 at a point substantially midway between the transmission 18 and worm 25 is a bevel gear 29 meshing with a like bevel gear 30, the gear 30 being fixed on a shaft 31 extending outwardly at right angles to the shaft 26. 85

The shaft 31 is rotatably mounted in a bearing 32 secured on the platform 16, and keyed to the outer end of the shaft is a sprocket 33 adapted for operative connection with an elevator mechanism 34 and distributor mechanism 35 hereafter described. 90

The elevator mechanism 34 includes an inverted U shaped frame 36 preferably of channel construction and including side legs 95

37 and 38 connected at their upper ends by a cross portion 39. The lower portion of the legs 37 and 38 extend downwardly across the walls 7 of the receptacle 5, with their lower ends in flush alignment with the receptacle bottom 8, the legs being rigidly secured to the walls 7 by suitable fastening means such as rivets.

In order that the frame 36 may in its assembled condition with the receptacle be applied to a pipe line, I provide a removable section 40 in the leg 37, the section being secured in assembled position by a clamp plate 41 attached to the leg by bolts 42.

Secured to the legs 37 and 38 at a point adjacent their upper ends are bearings 43 carrying a shaft 44, and keyed to the outer end of the shaft adjacent the leg 37 is a sprocket 45. The sprocket 45 is operatively connected with the sprocket 33 of the transmission mechanism by a chain belt 46 and thereby rotation of the sprocket 33 is imparted to the shaft 44.

Keyed to the shaft 44 and spaced slightly inwardly from the leg 38 is a sprocket 47 carrying a chain belt 48 which is fitted with fluid elevating buckets 49.

In order that the chain belt 48 may extend angularly from the sprocket 47 to produce a more effective dumping action for the buckets 49, an idler sprocket 50 is mounted in the receptacle, on a shaft 51 supported in bearings 52 and 53 secured respectively to the bottom and one of the side walls 7 of the receptacle at a point rearwardly of the frame 36.

Loosely mounted on the shaft 44 on the outer side of the leg 38 is a sprocket 54 having clutch jaws 55 engageable by a jaw clutch 56 slidably keyed to the outer portion of the shaft. The clutch 56 is connected with a shifting lever 57 pivoted on a bracket 58 attached to the leg 38 so that the clutch may be readily engaged with the sprocket for setting in operation the distributing mechanism 35 presently described.

The distributing mechanism 35 includes a support frame 59 spaced forwardly from the frame 36 and comprising side legs 60 and 61 connected at their upper ends by a cross rail 62, the lower portions of the legs being extended across the receptacle walls 7 and rigidly secured to the walls by rivets or like fastening means.

The leg 60 of the frame 59 is provided with a removable section 63 so that the frame in its assembled condition with the receptacle may be opened to permit its application to a pipe line, or to permit its removal from the pipe line. The leg section 63 is normally secured to the adjoining ends of the leg 60 by a clamp plate 64 attached to the section and to the leg by bolts 65.

Supported from the leg 60 by a bracket 66 is an angularly disposed chute 67 having its

rearward end elevated and spaced slightly below the horizontal center of the sprocket 47, and spaced outwardly from the sprocket sufficiently to provide clearance for the passage of the fluid elevating buckets 49 on the chain belt 48.

The lower or forward end of the chute terminates in an arcuate outwardly flared mouth 68 positioned centrally between the legs 60 and 61 so that the coating fluid flowing therefrom will be equally divided on opposite sides of the vertical center line of the pipe.

Fixed to the legs 60 and 61 at a substantially central position thereon are bearings 69 and 70 carrying a shaft 71, the shaft being provided with cranks 72 and 73. Mounted on the cranks are bearing collars 74 and 75 having radial bosses 76 and hooks 77 fixed in the bosses for the attachment of coil springs 78.

Attached to the coil springs 78 are binders 79 and a flexible strip 80, preferably of fabric is secured in the binders at its ends, and is of sufficient length to extend around the bottom of the pipe and to have free oscillating movement relative to the pipe when actuated by rotation of the shaft 71.

A set collar 81 is provided on the shaft 71 adjacent the bearing 70, and a sprocket 82 is keyed on the portion of the shaft extending outwardly from the bearing, and operatively connected with the sprocket 54 of the elevator shaft 44 by a chain belt 83.

Mounted at the upper ends of the legs 60 and 61 are adjustable arms 84 extending rearwardly and downwardly and having inset portions 85 at their lower ends rotatably supporting a concave roller 86 for engagement with the pipe to stabilize the apparatus in its tilting action on the larger drive roller 23.

The arms 84 are mounted on pivot bolts 87 extended through the posts and through spacer blocks 88 fitted in the leg channels for spacing the arms outwardly from the leg flanges. Heads 89 at the upper ends of the arms 84 are provided with arcuate slots 90, and brackets 91 fixed to the cross rail 62 are fitted with clamping bolts 92 whereby the arms are secured for holding the roller 86 in the desired position relative to the pipe line.

In removing or applying the apparatus to a pipe line, the bolts 92 are released and the arms 84 are swung upwardly on the pivot bolts 87, thereby releasing the roller 86 from its engagement with the pipe line.

In order to further stabilize the apparatus against sideward swinging movement on the pipe line, I prefer to provide a ground wheel 93 rotatable on the outer offset portion 94 of a shaft 95, the shaft being adjustably mounted in a bearing bracket 96 fixed to the frame 36.

A lever 97 fixed on the shaft 95 adjacent the frame 36 is adapted for adjustment and locking engagement with a head 98 secured to the frame, and thereby the shaft may be ad-

justed for properly tilting and balancing the apparatus for its travel over a pipe line.

In mounting the apparatus on a pipe line preparatory for a coating operation, the procedure is as follows:—

5 The chain belt 46 connecting the sprockets 33 and 45 is removed and the carrier frame 12 is disconnected from the receptacle 5 by removing the bolts whereby the beams 13 of the carrier are attached to the receptacle walls 7.

10 The short sections 40 and 63 are removed from their respective frames 36 and 59 so as to provide an opening to receive the elevated pipe line, and the roller 86 is elevated by 15 swinging the arms 84 upwardly. The receptacle portion of the apparatus is thus conditioned to be shifted sidewardly into assembled position on a pipe line by means of a portable hoisting apparatus.

20 After positioning the receptacle under the pipe line the leg sections are placed in assembled position and the arms 84 are adjusted so that the roller 86 rests on the pipe line.

The carrier frame 12 is then reassembled 25 on the receptacle and the chain belt 46 is placed on the sprockets 33 and 45 for operatively connecting the transmission mechanism with the elevator mechanism 34.

30 After the carrier frame has been reassembled with the receptacle, the arms 84 carrying the roller 86 are adjusted so that the weight of the apparatus is pivotally centered on the drive roller 23.

With the apparatus assembled on a pipe 35 line its operation is as follows:—

The receptacle 5 is filled with a coating fluid (preferably heated enamel) to be applied to the pipe line.

40 The motor 17 is set in operation, and the transmission lever 28 is shifted for transmitting rotation to the shaft 26 at a desired speed. Rotation of the shaft 26 causes rotation of the drive roller 23 which in turn causes the apparatus to be moved along on the pipe line in the direction of the motor.

45 Rotation is imparted to the drive sprocket 33 on the shaft 31 by the bevel gear 30 on the opposite end of the shaft engaging with the sprocket 29 on the shaft 26.

50 The chain belt connection between the sprockets 33 and 45 causes rotation to be imparted to the shaft 44 for operating the elevator belt 48 and causing the heated enamel to be elevated by the buckets 49 and emptied into 55 the chute 67.

55 The enamel flows downward through the chute and empties from the mouth 68 onto the pipe between the upwardly extending portions of the fabric strip 80.

60 When the apparatus is in operation the clutch 56 is engaged with the clutch portion 55 of the sprocket 54 so that the sprocket rotates with the shaft 44.

65 The sprocket 82 on the crank shaft 71 is operated by its chain belt connection with the

sprocket 54 and rotation of the crank shaft causes oscillating movement of the enamel distributing strip 80.

70 As the enamel flows onto the pipe it covers the upper surface thereof and the distributor strip 80 intercepts the surplus enamel in its return flow to the receptacle, and in its oscillating movement around the bottom side of the pipe causes the enamel to be thoroughly distributed over the bottom surface of the pipe.

75 The springs 78 are connected with the upper end of the distributor strip 80 so as to permit the strip to yield downwardly in passing pipe coupling or other irregularities in a pipe line.

80 What I claim and desire to secure by Letters Patent is:

1. In combination with an elevated pipe supported from the ground in horizontal position, paint-applying apparatus comprising a container supported from the pipe for movement therealong, a conveyor including buckets supported from the pipe for transferring paint from the container, and means supported from the container to receive paint from the conveyor for distribution to the pipe.

85 2. In combination with an elevated pipe supported from the ground in horizontal position, paint-applying apparatus comprising a container supported from the pipe for movement therealong, an elevator supported from the pipe for lifting paint from the container, means for moving the elevator, and means supported from the container to receive paint from the elevator for distribution to the pipe.

90 3. In combination with an elevated pipe supported from the ground in horizontal position, paint-applying apparatus comprising a container supported from the pipe for movement therealong, an elevator supported from the frame for lifting paint from the container, and a distributor supported from the container to receive paint from the elevator for distribution to the pipe and having an adjustable bracing member engageable with the pipe.

95 4. In a pipe-painting machine, a frame comprising parallel bars adapted to extend longitudinally of a pipe to be painted, a roller rotatably mounted in the frame and engageable with the pipe for supporting the frame from the pipe, means including a shaft for rotating the roller to move the frame along the pipe, a paint container having one end engaged with the frame, means including a bar and a pipe-engaging roller pivotally supported from the bar for supporting the other end of the container, and means including a wiping member supported from said bar for distributing paint from the container to the pipe.

100 5. In a pipe-painting machine, a frame

comprising parallel bars adapted to extend longitudinally of a pipe to be painted, a roller rotatably mounted in the frame and engageable with the pipe for supporting the frame from the pipe, means including a shaft for rotating the roller to move the frame along the pipe, a paint container having one end engaged with the frame, means including a bar pivoted on the frame and a pipe-engaging roller pivotally supported from the bar for supporting the other end of the container, means for fixing the bar in pivotally adjusted position, and means actuated from said shaft for distributing paint from the container to the pipe.

6. In a pipe-painting machine, a frame comprising parallel bars adapted to extend longitudinally of a pipe to be painted, a roller rotatably mounted in the frame and engageable with the pipe for supporting the frame from the pipe, means including a shaft for rotating the roller to move the frame along the pipe, a paint container having one end engaged with the frame, means including a bar and a pipe-engaging wheel pivotally supported from the bar for supporting the other end of the container, means for adjusting the relation of the pipe-engaging wheel to the pipe, an elevator supported from the frame including a conveyor movable into and out of the container, a chute supported from said bar to receive paint from the conveyor for gravity discharge to a portion of the pipe, and means including a rotatable shaft supported by said bar and a flexible member movable by the shaft in wiping relation with the pipe for distributing paint discharged from the chute to another portion of the pipe.

7. In a pipe coating machine, a container, a pair of spaced frame members fixed to the container, an elevator supported by one of the frame members, distributing means supported by the other frame member, a pipe engaging roller mounted in fixed position in the first named frame member, a pivotally adjustable bar having one end pivotally mounted on the other frame member and a pipe-engaging roller rotatably supported by the other end of said bar.

50 8. In a pipe coating machine including a container, and means including a frame for supporting the container on a pipe, an elevator including buckets supported by the frame for lifting material from the container, and means supported by the frame in receiving relation with the elevator for distributing material to the pipe.

In testimony whereof I affix my signature.
CLIFFORD F. MORAIN.
